FRAME FOR A CHAIR

John W. Caldwell, 2202 Pinecrest Drive,
Altadena, Calif. 91001

Filed Aug. 26, 1970, Ser. No. 24,706

Term of patent 14 years

Int. Cl. D6—02

U.S. Cl. D15—1

FIG. 1

FIG. 2

FIG. 4

FIG. 3

FIG. 1 is a three-quarters, oblique front view of a chair according to the invention;

FIG. 2 is a side elevation of the chair in FIG. 1;

FIG. 3 is a cross-section taken at line 3—3 of FIG. 2; and

FIG. 4 is a half view, in enlarged scale, of the plaque forming the back of the chair in FIG. 1, the half not shown on the other side of the centerline being the mirror image.

I claim:

The ornamental design for a frame for a chair, as shown and described.
